UNITED STATES PATENT OFFICE.

GLENN HENRY BOLUS, OF MANSFIELD, OHIO, ASSIGNOR TO THE OHIO BRASS COMPANY, OF MANSFIELD, OHIO, A CORPORATION OF NEW JERSEY.

TROLLEY-WIRE CLAMP.

1,364,026.

Specification of Letters Patent. Patented Dec. 28, 1920.

Application filed September 7, 1917. Serial No. 190,149.

To all whom it may concern:

Be it known that I, GLENN H. BOLUS, a citizen of the United States, residing at Mansfield, in the county of Richland and State of Ohio, have invented certain new and useful Improvements in Trolley-Wire Clamps, of which the following is a specification.

This invention relates to improvements in trolley wire clamps, and one of the principal objects of the invention is to provide an improved construction, combination and management of the several parts which will be simple in construction and effective and efficient in operation.

Another object of my invention is to provide an improved device of this character having positive action and adapted to be readily inserted into and removed from operative position.

A further object is to provide an improved trolley clamp having means for detachably and adjustably connecting the clamp to its support on hanger and having swivel jaws whereby a perfect alinement of the trolley wire may be obtained when the parts are secured together.

With these and other objects in view, which will be apparent in the specification, my invention consists in the features of novelty in the construction, combination and arrangement of the parts hereinafter more fully described and claimed, and shown in the accompanying drawings illustrating the embodiment of my invention in which:—

Figure 1 is a longitudinal vertical section of a trolley clamp embodying the principles of my invention.

Fig. 2, is a transverse sectional view of the device, showing the several parts in the positions they assume when gripped upon the trolley wire.

Fig. 3, is an end view of the clamp, removed from the hanger or support and showing the jaws in open position.

Fig. 4, is a sectional view taken on the line 4—4 Fig. 2.

Referring to the drawings in which similar reference characters indicate like parts in the different views, (1) generally indicates an insulated hanger or support having suitable means (2) whereby it is rigidly secured or suspended in the usual manner.

55 Embedded within the insulation material

(3), is a stud (4) having its lower end (5) provided with screw threads to receive the threaded socket (6). The threaded socket (6), comprises a cylindrical body (7), having a hexagonal flange (8), which is 60 slidably received within the hexagonal opening (9) provided in one end of the adjusting sleeve (10), the opposite end of the said sleeve being provided with a wedging surface (11) and an opening (12), adapted to 65 loosely receive the body (7) of the socket. The exterior surface of the adjusting sleeve (10) is preferably of hexagon shape and which when rotated causes the threaded socket (6) to screw on the threaded end (5) 70 of the stud (4) by means of engagement with the hexagonal flange (8) as shown in Fig. 4. A connecting pin (13) projects through a suitable aperture formed in the end of the socket (6) wherein it is loosely 75 mounted and supported by means of the head (14) engaging the end surface of the said socket. The connecting pin (13) has an aperture (15) formed adjacent the end thereof adapted to receive the pin (16). 80

The clamping member comprises a pair of interchangeable clamping jaws (17) each provided with apertured lugs, (18) the lower ends of the jaws being preferably constructed as shown for the purpose of 85 gripping the trolley wire (19) when in clamped position. Each of the jaws (17) comprises a power arm (20) flared outwardly to provide a conical wedging surface (21) the purpose of which will be described 90 hereinafter.

It will be noted in Fig. 1, that the connecting pin (13) is positioned between the central lugs (18) of the clamping members (17) thereby retaining the conical 95 wedging surfaces (21) of the clamping members in line with the wedging surface (11) of the adjusting collar (10). Inasmuch as the adjusting collar (10) and the threaded socket (6) are locked against relative rotative movement by means of hexagonal opening (9) and the flange (8), positioned therein, a rotation of the collar, in one direction, will cause the socket (6) to screw on the end (5) of the stud (4). This 105 movement will adjust the socket (6) upon the stud (4) to draw the jaws (17) upwardly and also the collar (10) since it is free to slide on the socket and rests upon the jaws (17).

100

110

Continued rotation of the parts (6) and (10) will cause the upper face of the collar (10) to finally engage the face A of the hanger thereby arresting the upward movement of the collar (10) but not of the socket (6) which will continue to move upward drawing with it the jaws (17). As the rotation of the parts (6) and (10) is continued the power arms (20) of the jaws (17) will be forced apart, through engagement with the surface (11) about the fulcrum pin (16) thereby causing the clamping jaws (17) to grip the wire. Rotative movement of the collar (10) in the opposite direction releases the grip of the jaws from the wire.

Having thus fully described my invention, and shown one form embodying the same, I do not wish to be limited to the details of the construction shown, since these can be obviously changed without departing from the spirit and scope of the invention, what I claim, and desire to secure by Letters Patent is:—

- 25 1. A trolley clamp for attachment to a hanger comprising a pair of clamping jaws, means securing the jaws together but permitting a relative movement of the jaws, a stem secured between the jaws, a supporting socket mounted on the stem and having a rotatable and a sliding longitudinal movement relative to the stem but such movements being independent of each other, means limiting the longitudinal movement 30 of the socket relative to the stem, means for securing the clamp to the hanger and a collar coacting with the socket and engaging the hanger and jaws to secure the clamp to the hanger and trolley wire.
- 35 2. A trolley wire clamp for attachment to a hanger comprising a pair of clamping jaws, a pin pivotally securing the jaws together, a stem mounted on the pin, a supporting socket rotatably mounted on the

stem and having independent rotatable and longitudinal movement therewith, means limiting the longitudinal movement, means on the supporting socket to secure the clamp to the hanger and an adjustable collar mounted on the socket and interlocked therewith against relative rotation but having a longitudinal movement relative thereto and engaging the jaws and hanger to secure the clamp to the trolley wire when the collar and supporting socket are rotated.

3. A trolley wire clamp for attachment to a hanger comprising a pair of clamping jaws, a pin pivotally securing the jaws together, a supporting socket rotatably mounted between the jaws, means on the socket 60 for securing the clamp to the hanger, a stem mounted in the socket and secured to the pin against rotation, means on the socket and pin permitting relative rotation and longitudinal movement and a collar mounted on 65 the socket and moving longitudinal thereof but interlocked against relative rotation therewith and engaging the jaws and hanger to secure the clamp to the trolley wire when the collar and supporting socket are 70 rotating.

4. A trolley wire clamp for attachment to a hanger comprising a pair of clamping jaws, a pin pivotally securing the jaws together, a supporting socket rotatably 75 mounted between the jaws, means on the socket to engage the hanger and secure the clamp to the hanger, a stem mounted in the socket and secured to the pin, a shoulder on the stem co-acting with a shoulder in 80 the socket permitting a limited longitudinal movement of the socket relatively to the stem and a collar mounted on the socket to move longitudinally thereof and engaging the hanger and jaws to actuate the jaws to 85 grip the trolley wire.

In testimony whereof I affix my signature.
GLENN HENRY BOLUS.
